UNITED STATES PATENT OFFICE

164,423

SIGNAL FLARE

Tyler Howell, Jonesville, Mich.

Application June 29, 1951, Serial No. 15,712

Term of patent 14 years

(Cl. D72—1)

To all whom it may concern:

Be it known that I, Tyler Howell, a citizen of the United States of America, residing at Jonesville, county of Hillsdale, and State of Michigan, have invented a new, original, and ornamental Design for a Signal Flare, of which the following is a specification, reference being had to the accompanying drawing, forming a part thereof wherein:

Fig. 1 is a top view of a signal flare, showing my new design; and

Fig. 2 is a side elevational view thereof.

I claim:

The ornamental design for a signal flare, as shown.

TYLER HOWELL.
